ENGINE GOVERNOR

Marion Mallory, Detroit, Mich.

Application November 25, 1942, Serial No. 466,961

33 Claims. (Cl. 123—103)

This invention relates to a governor for controlling the speed of an internal combustion engine.

It is the object of this invention to produce a governor for controlling the speed of an internal combustion engine which is considerably more efficient in operation and more simple than governors heretofore known.

This invention contemplates an engine governor which will control the speed of an internal combustion engine at any predetermined desired speed with greater precision and nicely than heretofore possible.

In the drawing:

Fig. 1 is an elevation partly in section showing my engine speed governor.

Figs. 2, 3 and 4 are sections along the lines 2—2, 3—3, and 4—4 of Fig. 1.

Referring more particularly to the drawing there is shown a governor housing 1 having an inlet 2 and an outlet 3. The governor housing is adapted to be connected into the intake manifold of an internal combustion engine on the engine side of the carburetor.

The housing is provided with a venturi 3. A 25 governor valve 4 of the butterfly type is mounted within the housing on shaft 5 journaled in housing 1. Crank 6 is fixed on shaft 5 outside of the housing 1. A tension spring 7 having one end connected to the crank 6 as at 8 and the other end connected to a lug on the housing as at 9 tends to keep the governor throttle valve 4 open. The governor valve 4 is an unbalanced valve having its greatest area or longest end positioned below the shaft 5 as shown in Fig. 1. The governor can be used for controlling the air charge of an internal combustion engine where injection is used to inject the fuel into the engine instead of using a carburetor. Thus, the governor valve 4 is unbalanced so that the gas flowing through the housing 1 by valve 4 tends to open the valve instead of tending to close it as in the conventional velocity governor.

A suction device is provided for operating governor valve 4. This suction device comprises a housing 12 and flexible diaphragm 11. Diaphragm 11 is connected by rod 10 to crank 6. Housing 12 to the left of diaphragm 11 communicates with atmosphere whereas housing 12 to the right of diaphragm 11 communicates only with and is connected into conduit 13. Conduit 14 communicates at one end with conduit 13 and at the other end with orifice 15 in venturi 3. Conduit 16 communicates at one end with conduit 13 and at the other end with orifice 17 in

venturi 18 in the intake passageway. A restriction in the form of a manually operated screw-type needle valve 19 is provided in conduit 13 between suction device 12 and the point at which conduit 13 communicates with conduits 14 and 16. Needle valve 19 can be screwed inwardly to restrict orifice 50 in conduit 13 and thereby restrict the flow of fluid through conduit 13 to and from the suction device 12 and screwed outwardly to decrease this restriction. Thus, by means of needle valve 19 the pressure in suction device 12 can be adjusted or regulated without affecting the pressures in conduits 13, 14 and 16. By adjusting needle valve 19 inwardly, the power of the suction device 12 is reduced, and by adjusting the needle valve outwardly, the power of the suction device 12 is increased. It is very important that the needle adjustment 19 be located parallel to conduits 14 and 16 and at a point that the pressures in conduits 13, 14 and 16 are not effected when adjustment is being made. Venturis 3 and 18 are valuable for low speed governing but are not essential, although preferred, for governing at the higher engine speeds.

Conduit 13 is arranged to communicate with atmosphere but this communication is controlled by a centrifugally operated governor valve. The centrifugally operated governor valve is arranged so that it can be mounted within the distributor housing 20 of the ignition system for the internal combustion engine. The distributor is not shown in detail but the distributor arm is designated 21, the cam 22, the distributor points 23 and the wires 24 leading to the spark plugs.

The distributor shaft 25 is journaled in the housing 20 by means of bushings 26 and 27 which are spaced as at 28 to provide a circumferential clearance about the shaft 25. The shaft 25 is provided with a diametrical opening 29 which continuously communicates with clearance 28 as the shaft rotates. Clearance 28 continuously communicates with conduit 13 through passageway 30 in the housing 20. Shaft 25 is provided with a cylindrical enlarged portion 31, the longitudinal axis of which extends perpendicularly to the axis of rotation of shaft 25.

Cylinder 31 is provided with an opening 32 of hexagonal section in which is reciprocably mounted the centrifugally operated valve 33 (Fig. 2). Valve 33 is centrifugally unbalanced so that centrifugal force will tend to move the valve outwardly from the axis about which it rotates and thereby tend to close the orifice 33. Valve 33 is provided with a groove 34 in its outer surface. Shaft 25 is provided with a passageway 35 which

communicates at one end with opening 32 and at the other end with passageway 29. Valve 33 is retained in the cylinder 31 by a threaded plug 37 having an orifice 38 through which communication is established between the interior of housing 20 and opening 32. Housing 20 communicates with atmosphere through opening 39. Valve 33 is normally retained in open position by tension spring 40, one end of which is connected to the valve 33 and the other end of which is connected to a plug 41 of square section mounted in opening 42 also of square section within cylinder 31. The plug 41 has a threaded connection with adjusting screw 43. Thus, by turning adjusting screw 43, plug 42 can be moved inwardly or outwardly to vary the tension of spring 40 and thereby determine the speed at which valve 33 closes or restricts orifice 38. Orifices 15 and 17 are preferably quilled as shown.

The operation of the device is as follows: The tension of spring 40 will be adjusted so that valve 33 will close or restrict orifice 38 at whatever predetermined speed desired. As shown, the engine is operating below the predetermined governed speed. At this time suction device 12 communicates with atmosphere through conduit 13, passageways 30, 29, 36, 34, 38 and 39. If the carburetor throttle valve is opened to gradually increase the speed of the engine, the velocity of the fuel-mixture charge flowing through venturi 3 by quilled orifice 15 and by quilled orifice 17 will gradually increase and as the velocity increases the vacuum created at orifices 15 and 17 will increase but this vacuum is air bled through orifice 39, passageways 38, 36, 29 and conduit 13. However, as soon as the engine reaches the predetermined governed speed, valve 33 will momentarily close orifice 38 and the air bleeding of orifices 15 and 17 will cease whereupon a vacuum will immediately be created in suction device 12 and governor valve 4 will move toward closed position. After valve 33 closes the speed of the engine will increase slightly (a few revolutions per minute) beyond the predetermined governed speed momentarily and then drop back to the governed speed. As suction device 12 pulls governor valve 4 towards closed position, the manifold suction or vacuum at orifice 17 will increase but this high vacuum is not impressed upon diaphragm 11 because it is bled down through orifice 15 and conduit 14. In other words, orifice 15 changes from a suction orifice to an air bleed orifice when valve 4 moves toward closed position.

When the governor valve 4 closes, the vacuum in the manifold on the engine side of the governor valve might raise as high as 25" of mercury whereas the vacuum in the suction device 12, due to the bleeding action of orifice 15 and conduit 14, will only reach from, say, about 7" to 10" of mercury. This inter-action of orifices 15 and 17 to blend down the vacuum in suction device 12 is beneficial in that it assists in preventing the valve 4 from flipping closed too quickly which would cause the engine to slow down too much and in turn cause valve 4 to flip open again too quickly and cause the engine speed to increase rapidly. In other words, this blending down of the manifold vacuum assists the governor valve to operate more smoothly and prevents surging of the engine, that is, abrupt and substantial changes in the speed of the engine from the governed speed as the governor valve opens and closes.

Should the engine start to slow down slightly

due to increased load, the lower vacuum at orifice 17 permits the spring 7 to start valve 4 toward an open position. Naturally, as the governor valve 4 moves toward open position, the vacuum drops rapidly at orifice 17, but orifice 15 now becomes a suction orifice due to increased velocity through venturi 3 by orifice 15 and thereby prevents a sudden drop of suction in the suction device. Thus, valve 4 closes smoothly and opens smoothly which prevents surging and maintains a substantially constant engine speed instead of a variable or surging speed.

The governor valve 4 can be used in conjunction with the conventional manually operated carburetor throttle valve or it can be used as the sole throttle valve in the intake passageway. The governor housing 2 can be part of the carburetor; the governor valve 4 serving as the carburetor throttle and the venturi above the throttle can be the carburetor venturi.

Heretofore one of the major troubles with all governor valves controlled by the manifold vacuum has been that they flip closed abruptly as soon as they start to close. Naturally, as soon as these governor valves of the prior art flip closed, the manifold vacuum becomes very high and holds the governor valve closed until the engine speed is almost reduced to idle or low enough so that the vacuum would drop considerably to permit the spring to open the valve. The governor valve then flies open abruptly and the engine races until it again reaches its governed speed whereupon the governor trips closed again and remains plastered or almost closed until the engine speed again decreases almost to idle. This major trouble or defect in the prior art governor valves controlled by manifold vacuums has been obviated in my governor.

The governor valve 4 is unbalanced so that the engine suction acting directly on this valve tends to open it, that is, when valve 4 is closed the difference in pressure conditions obtaining in the intake passageway above and below the valve tends to open it, but the manifold or engine suction when it acts indirectly on the valve through the diaphragm or suction device 11, 12, tends to close the governor valve 4. This condition is very desirable because it prevents the governor valve 4 from plastering or flipping shut and thereby assists in preventing surging of the engine. If the throttle valve is unbalanced so that the engine suction acting directly on the throttle valve tends to close it, the vacuum on the engine side of the governor valve when it reaches closed position is so high that the governor valve will plaster or flip shut because the engine suction will have a closing effect on the governor valve in addition to the diaphragm action tending to close the governor valve. Even if the governor valve is perfectly balanced so that the suction will not affect it, it will still tend to flip or plaster closed due to the increased power in the suction device when the throttle valve is near closed position. Therefore, it is desirable and preferable that the throttle valve should be unbalanced as I show it so that the engine suction acting directly on the governor throttle valve opposes the engine suction or power applied indirectly on the governor valve by the diaphragm. This assists in preventing the governor valve from plastering closed and thereby assists in preventing surging of the engine.

Assuming that adjustment screw 43 has been set so that spring 40 would permit the governor

valve to close at an engine speed of 3000 R. P. M., the vacuum caused by the velocity of the air or charge flowing by orifices 15 and 17 would start valve 4 to move towards a closed position as the engine speed approached 3000 R. P. M. The vacuum at orifice 17 would increase rapidly as valve 4 moved toward closed position, but the higher the vacuum in line 13 and valve chamber 32 became, the more difficult it becomes to close valve 33 because the suction through orifice 38 tends to hold valve 33 away from its seat 51 and prevent plastering of valve 33, i. e., prevent valve 33 from flipping closed abruptly.

As valve 33 starts to close, the vacuum increase behind it, that is, in chamber 32 which actually prevents valve 33 from remaining closed or plastering. When the engine reaches its predetermined governed speed, say, 3000 R. P. M., valve 33 does completely close orifice 38 but only momentarily so that enough suction or vacuum will be created in the suction device to start valve 4 moving toward closed position. The pressure acting on valve 33 throughout the area of seat 51 is always atmospheric whereas the pressure in chamber 32 when the engine is running is sub-atmospheric. Thus, atmospheric pressure is always acting on valve 33 and tending to open it or hold it open in opposition to the centrifugal force tending to close it. However, as soon as valve 4 moves toward closed position, the vacuum increases in conduit 13 and chamber 32 and holds valve 33 a slight distance off from its seat. If the engine speed is decreased, the vacuum also decreases with the decreases in the centrifugal force tending to close valve 33. If the engine speed increases, so will the centrifugal force acting on valve 33. Valve 33 stays almost closed and its opening and closing varies with the speed as well as with the vacuum conditions obtaining in line 13 and chamber 32. Thus, the centrifugal force acting to close valve 33 is counter-balanced by or played against the tension of spring 40 plus the suction acting on valve 33. It is for this reason that the opening and closing of the governor valve 4 follows the engine load very closely to maintain a predetermined governed speed, that is, as the engine load increases, the governor valve opens to admit more charge to the engine and as the engine load decreases the governor valve closes to decrease the fuel charge to the engine and thereby maintain the predetermined governed speed of the engine with remarkable uniformity.

The above is believed to be an accurate description of the mode of operation of the above described governor, but in any event a governor constructed as above described functions to maintain the engine speed at the predetermined governed speed with practically no surging and only very minor variations in engine speed as the engine load is increased or decreased. Even under a large and abrupt load increase (assuming always, of course, that the total load is less than the power developed by the engine), the engine speed will decrease momentarily only slightly from the governed speed anywhere from a few to about 100 R. P. M. depending upon load conditions.

Another advantage of my governor is that it functions efficiently to govern the engine, as above described, at any predetermined speed desired regardless of whether this desired speed is high or low or in between. Presently used governors of the prior art are inefficient, particularly at low speeds, and none of them function without

considerable engine surge and tail, i. e., considerable overrunning and underrunning of the governed speed as load conditions change.

It should be noted that the centrifugal valve arrangement shown lends itself admirably to incorporation in the standard ignition distributor. This effects an appreciable economy in the manufacture and installation of the governor in comparison with the engine governors heretofore known.

I claim:

1. In an internal combustion engine having an intake passageway, a governor valve for controlling the flow of fluid through said passageway, a suction operated device connected to said governor valve, a conduit connecting the suction device into the intake passageway on the engine side of the said governor valve, and a second conduit connecting the suction device with atmosphere, the improvement comprising a centrifugally unbalanced valve arranged to revolve about an axis in accordance with the speed of the engine for controlling communication between the second conduit and atmosphere, said centrifugally unbalanced valve responding to an increase in centrifugal force and tending to close said second conduit to atmosphere against the suction in the intake passageway whenever the engine attains a predetermined speed whereby the suction device responds to move said governor valve toward closed position.

2. In an internal combustion engine having an intake passageway, a governor valve for controlling the flow of fluid through said passageway, a suction operated device connected to said governor valve, and a conduit connecting the suction device into the intake passageway on the engine side of the said governor valve, the improvement comprising a valve housing rotated in accordance with the speed of the engine and having a port to atmosphere, a second conduit connecting the suction device with said valve housing, said first and second conduits being in communication with each other, and a centrifugally unbalanced valve mounted in said housing tending to close said port to atmosphere against the suction in the intake passageway on the engine side of said governor valve, whenever the engine attains a predetermined speed whereby the suction device responds to move said governor valve toward closed position.

3. In an internal combustion engine having an intake passageway, a governor valve for controlling the flow of fluid through said passageway, a suction operated device connected to said governor valve, a conduit connecting the suction device into the intake passageway on the engine side of the said governor valve, a second conduit connecting the suction device with atmosphere, and a centrifugally unbalanced valve operated in accordance with the speed of the engine for controlling communication between the second conduit and atmosphere, said centrifugally unbalanced valve tending to close said second conduit to atmosphere whenever the engine attains a predetermined speed whereby the suction device responds to move said governor valve toward closed position, a third conduit connecting the suction device into the intake passageway on the atmosphere side of the governor valve.

4. In an internal combustion engine having an intake passageway, a governor valve for controlling the flow of fluid through said passageway, a suction operated device connected to said governor valve, a conduit connecting the suction de-

vice into the intake passageway on the engine side of the said governor valve, a valve housing rotated in accordance with the speed of the engine and having a port to atmosphere, a second conduit connecting the suction device with said valve housing, and a centrifugally unbalanced valve mounted in said housing tending to close said port to atmosphere whenever the engine attains a predetermined speed whereby the suction device responds to move said governor valve toward closed position, a third conduit connecting the suction device into the intake passageway on the atmosphere side of the governor valve.

5. In an internal combustion engine having an intake passageway, a governor valve for controlling the flow of fluid through said passageway, a suction operated device connected to said governor valve, a conduit connecting the suction device into the intake passageway on the engine side of the said governor valve, a valve housing rotated in accordance with the speed of the engine and having a port to atmosphere, a second conduit connecting the suction device with said valve housing, and a centrifugally unbalanced valve mounted in said housing tending to close said port to atmosphere whenever the engine attains a predetermined speed whereby the suction device responds to move said governor valve toward closed position, and resilient means tending to hold said valve open in opposition to the centrifugal force tending to close the valve, the said valve being arranged in said housing so that it tends to close said port in opposition to atmospheric pressure, a third conduit connecting the suction device into the intake passageway on the atmosphere side of the governor valve.

6. In an internal combustion engine having an intake passageway, a governor valve for controlling the flow of fluid through said passageway, a suction operated device connected to said governor valve, a conduit connecting the suction device with atmosphere externally of said passageway, a second conduit connecting the first mentioned conduit with the intake passageway on the engine side of the governor valve, the improvement comprising a centrifugally unbalanced valve operated in accordance with the speed of the engine for controlling communication between the first-mentioned conduit and atmosphere, said centrifugally unbalanced valve tending to close said first-mentioned conduit to atmosphere against the suction in the intake passageway on the engine side of said governor valve whenever the engine attains a predetermined speed whereby the suction device responds to move said governor valve toward closed position, an adjustable valve for controlling the first mentioned conduit mounted between the suction device and the point at which the other conduit connects into the first mentioned conduit.

7. In an internal combustion engine having an intake passageway, a governor valve for controlling the flow of fluid through said passageway, a suction operated device connected to said governor valve, a conduit connecting the suction device with atmosphere, a second conduit connecting the first conduit into the intake passageway on the atmosphere side of the governor valve, a centrifugally unbalanced valve operated in accordance with the speed of the engine for controlling communication between the second conduit and atmosphere, said centrifugally unbalanced valve tending to close said sec-

ond conduit to atmosphere whenever the engine attains a predetermined speed whereby the suction device responds to move said governor valve toward closed position, and an adjustable valve for the first mentioned conduit positioned between the suction device and the point at which the second and third conduits connect into the first conduit whereby the pressure condition in the suction device can be adjusted without affecting the pressure conditions in the second and third conduits.

8. The combination as claimed in claim 1 wherein the governor valve is unbalanced so that the suction in the intake passageway on the engine side of the governor valve tends to open said governor valve.

9. The combination as claimed in claim 2 wherein the governor valve is unbalanced so that the suction in the intake passageway on the engine side of the governor valve tends to open said governor valve.

10. In an internal combustion engine having an intake passageway, a governor valve for controlling the flow of fluid through said passageway, a suction operated device connected to said valve, a conduit connecting the suction device into the intake passageway on the engine side of said valve, a second conduit connecting the suction device into the intake passageway on the atmosphere side of said valve, a third conduit connected into said suction device and leading to atmosphere, and valve mechanism for opening and closing said third conduit to and from atmosphere comprising a valve housing rotated in accordance with the speed of the engine and having a port communicating with said third conduit and a port to atmosphere, a centrifugally controlled valve mounted in said housing and arranged to close said port to atmosphere whenever the engine attains a predetermined speed whereby the suction device responds to move said governor valve toward closed position.

11. In an internal combustion engine having an intake passageway, a governor valve for controlling the flow of fluid through said passageway, said governor valve being unbalanced so that the flow of the charge through said intake passageway tends to open said governor valve, a suction operated device connected to said valve, a conduit connecting the suction device into the intake passageway on the engine side of said valve, a second conduit connecting the suction device into the intake passageway on the atmosphere side of said valve, a third conduit connected into said suction device and leading to atmosphere, and valve mechanism for opening and closing said third conduit to and from atmosphere comprising a valve housing rotated in accordance with the speed of the engine and having a port communicating with said third conduit and a port to atmosphere, a centrifugally controlled valve mounted in said housing and arranged to close said port to atmosphere whenever the engine attains a predetermined speed whereby the suction device responds to move said governor valve toward closed position.

12. In an internal combustion engine having an intake passageway, a governor valve for controlling the flow of fluid through said passageway, a spring tending to hold said valve open, a suction operated device connected to said valve, a conduit connecting the suction device into the intake passageway on the engine side of said valve, a second conduit connecting the suction device into the intake passageway on the atmos-

phere side of said valve, a third conduit connected into said suction device and leading to atmosphere, and valve mechanism for opening and closing said third conduit to and from atmosphere comprising a valve housing rotated in accordance with the speed of the engine and having a port communicating with said third conduit and a port to atmosphere, a centrifugally controlled valve mounted in said housing and arranged to close said port to atmosphere whenever the engine attains a predetermined speed whereby the suction device responds to move said governor valve toward closed position.

13. In an internal combustion engine having an intake passageway, a governor valve for controlling the flow of fluid through said passageway, a suction operated device connected to said valve, a conduit connecting the suction device into the intake passageway on the engine side of said valve, and a second conduit connecting the suction device into the intake passageway on the atmosphere side of said valve, the improvement comprising a third conduit connected into said suction device and leading to atmosphere, a rotary shaft having a passageway therein continuously in communication with said third conduit and rotated in accordance with the speed of the engine, a valve housing mounted on said shaft for rotation therewith, the interior of said valve housing being in communication with the passageway in said shaft and having a port to atmosphere, and a centrifugally unbalanced valve mounted within said housing for closing said port to atmosphere when the shaft reaches a predetermined speed whereby the suction device responds to move said governor valve toward closed position, said valve itself constituting the weight which responds to the centrifugal force caused by rotation of said housing.

14. In an internal combustion engine having an intake passageway, a governor valve for controlling the flow of fluid through said passageway, a suction operated device connected to said valve, a conduit connecting the suction device into the intake passageway on the engine side of said valve, a second conduit connecting the suction device into the intake passageway on the atmosphere side of said valve, a third conduit connected into said suction device and leading to atmosphere, an ignition distributor shaft rotatable in accordance with the speed of the engine and having a passageway therein communicating at all times with said third conduit, a valve housing fixed on said shaft, the interior of said housing communicating with the passageway in said shaft, a port to atmosphere in said valve housing, and a centrifugally controlled valve mounted within said housing for closing said port to atmosphere when the shaft reaches a predetermined speed whereby the suction device responds to move said governor valve toward closed position.

15. In an internal combustion engine having an intake passageway, a governor valve for controlling the flow of fluid through said passageway, a suction operated device connected to said valve, a conduit connecting the suction device into the intake passageway on the engine side of said valve, a second conduit connecting the suction device into the intake passageway on the atmosphere side of said valve, a third conduit connected into said suction device and leading to atmosphere, an ignition distributor shaft rotatable about a vertical axis in accordance with the speed of the engine and having a passageway therein communicating at all times with said third conduit,

10 a valve housing fixed on said shaft, the interior of said housing communicating with the passageway in said shaft, a port to atmosphere in said valve housing, and a centrifugally controlled valve mounted within said housing for closing said port to atmosphere when the shaft reaches a predetermined speed whereby the suction device responds to move said governor valve toward closed position.

15 16. In an internal combustion engine having an intake passageway, a governor valve for controlling the flow of fluid through said passageway, a suction operated device connected to said valve, a conduit connecting the suction device into the intake passageway on the engine side of said valve, a second conduit connecting the suction device into the intake passageway on the atmosphere side of said valve, a third conduit connected into said suction device and leading to atmosphere, and valve mechanism for opening and closing said third conduit to and from atmosphere comprising a valve housing rotated in accordance with the speed of the engine and having a port communicating with said third conduit and a port to atmosphere, a centrifugally controlled valve mounted in said housing and arranged to close said port to atmosphere whenever the engine attains a predetermined speed whereby the suction device responds to move said governor valve toward closed position, and means cooperating with one of the above-mentioned first and second conduits for increasing the vacuum produced in the suction device by the flow of the fluid through said intake passageway when the centrifugally controlled valve is closed.

20 17. In an internal combustion engine having an intake passageway, a governor valve for controlling the flow of fluid through said passageway, a venturi in said passageway on the atmosphere side of the governor valve, a suction operated device connected to said valve, a conduit connecting the suction device into the venturi, a second conduit connecting the suction device into the intake passageway on the engine side of said valve, a third conduit connected into said suction device and leading to atmosphere, and valve mechanism for opening and closing said third conduit to and from atmosphere comprising a valve housing rotated in accordance with the speed of the engine and having a port communicating with said third conduit and a port to atmosphere, a centrifugally controlled valve mounted in said housing and arranged to close said port to atmosphere whenever the engine attains a predetermined speed whereby the suction device responds to move said governor valve toward closed position.

25 18. In an internal combustion engine having an intake passageway, a governor valve for controlling the flow of fluid through said passageway, a venturi in said passageway on the atmosphere side of said valve and a venturi in said passageway on the engine side of said valve, a suction operated device connected to said valve, a conduit connecting the suction device into the venturi on the engine side of said valve, a second conduit connecting the suction device into the venturi on the atmosphere side of said valve, a third conduit connected into said suction device and leading to atmosphere, and valve mechanism for opening and closing said third conduit to and from atmosphere comprising a valve housing rotated in accordance with the speed of the engine and having a port communicating with said third conduit and a port to atmosphere, a centrifugally controlled valve mounted in said housing and ar-

ranged to close said port to atmosphere whenever the engine attains a predetermined speed whereby the suction device responds to move said governor valve toward closed position.

19. In an internal combustion engine having an intake passageway, a governor valve for controlling the flow of fluid through said passageway, a suction operated device connected to said valve, a conduit connecting the suction device into the intake passageway on the engine side of said valve, the improvement comprising a second conduit connected into said suction device and leading to atmosphere, a rotary shaft having a passageway therein continuously in communication with said second conduit and rotated in accordance with the speed of the engine, a valve housing mounted on said shaft for rotation therewith, the interior of said valve housing being in continuous communication with the passageway in said shaft and having a port to atmosphere, and a centrifugally unbalanced valve mounted within said housing for radial movement toward and away from the axis of rotation of said shaft and housing and tending to close said port to atmosphere when the shaft reaches a predetermined speed whereby the suction device responds to move said governor valve toward closed position, said valve itself constituting the weight which responds to the centrifugal force created by rotation of said valve housing, and resilient means opposing the closing of said centrifugally unbalanced valve.

20. In an internal combustion engine having an intake passageway, a device for governing the speed of the engine free from substantial surges in engine speed comprising a governor valve for controlling the flow of fluid through said passageway, a device actuated by suction from a point in said passageway between the governor valve and the engine and having an operative connection with said governor valve, an air bleed orifice to atmosphere for said suction actuated device, a valve responsive to changes in engine speed for controlling said air bleed orifice, said air bleed valve closing in opposition to the suction from said intake passageway as the engine reaches its governed speed whereby the governor valve is closed by said suction actuated device in response to the suction impressed upon said suction actuated device and the suction in the intake passageway between the governor valve and the engine increases and said suction moves the air bleed valve slightly away from its seat to air bleed from atmosphere the suction impressed upon the suction device to less than the suction obtaining in the intake passageway between the governor valve and engine under such operating conditions.

21. In an internal combustion engine having an intake passageway, a device for governing the speed of the engine free from substantial surges in engine speed comprising a governor valve for controlling the flow of fluid through said passageway, a device actuated by suction from a point in said passageway between the governor valve and the engine and having an operative connection with said governor valve, an air bleed orifice to atmosphere for said suction actuated device, a centrifugally unbalanced valve responsive to changes in engine speed for controlling said air bleed orifice, said valve itself constituting the centrifugal weight which responds to changes in the engine speed, said air bleed valve closing due to centrifugal force as the engine reaches its governed speed and in opposition to the suction from said intake passageway whereby the governor valve is closed by said suction actuated device in response

to the suction impressed upon said suction actuated device and the suction in the intake passageway between the governor valve and the engine increases and said suction moves the said air bleed valve slightly away from its seat to air bleed from atmosphere the suction impressed upon the suction device to less than the suction obtaining in the intake passageway between the governor valve and engine under such operating conditions.

22. In an internal combustion engine having an intake passageway, mechanism for governing the speed of the engine comprising a governor valve for controlling the flow of fluid through said passageway, a suction actuated device having an operative connection with said governor valve, an orifice located in said passageway on the engine side of said throttle valve, a conduit connecting said orifice with said suction device, an air bleed orifice to atmosphere, a second conduit connecting said air bleed orifice with the suction device and the aforementioned conduit, a valve for controlling said air bleed orifice and subject to the suction obtaining in the intake passageway on the engine side of the throttle valve, means responsive to changes in engine speed for controlling said air bleed valve, the said speed responsive means tending to close said air bleed valve in opposition to said suction from said intake passageway as the engine reaches its governed speed, resilient means opposing the closing of said air bleed valve, the force urging said valve closed when said engine reaches its governed speed being co-ordinated with the force of the resilient means and the suction from the intake passageway tending to open said air bleed valve whereby when the suction device responds to the intake passageway suction to close said governor valve the suction obtaining in the intake passageway on the engine side of the governor valve will co-act with the said resilient means in opposition to the force tending to close said air bleed valve and hold the air bleed valve slightly open to air bleed the suction impressed upon the suction device to less than the suction obtaining in the intake passageway under such operating conditions.

23. The combination as claimed in claim 22 including a third conduit connecting the suction device with an orifice in the intake passageway on the atmosphere side of said governor valve whereby the orifice between the governor valve and atmosphere plays the role of an air bleed to the other orifice in said intake passageway when the said governor valve moves toward closed position and said orifice between the governor valve and atmosphere ceases to be an air bleed and becomes a suction orifice when the governor valve moves toward open position.

24. In an internal combustion engine having an intake passageway, mechanism for governing the speed of the engine comprising a governor valve for controlling the flow of fluid through said passageway, a suction actuated device having an operative connection with said governor valve, a venturi located in said intake passageway on the engine side of said throttle valve, an air bleed orifice, an orifice in said venturi, a conduit connecting said air bleed orifice with the suction device and the aforementioned orifice, a valve for controlling said air bleed orifice and subject to the suction obtaining in the intake passageway on the engine side of the throttle valve, means responsive to changes in engine speed for controlling said air bleed valve, the said speed responsive means tending to close said air bleed valve in op-

position to said suction from said intake passageway as the engine reaches its governed speed, resilient means opposing the closing of said air bleed valve, the force urging said air bleed valve closed when said engine reaches its governed speed being coordinated with the force of the resilient means and the suction from the intake passageway tending to open said air bleed valve whereby when the suction device responds to the intake passageway suction to close said governor valve the suction obtaining in the intake passageway on the engine side of the governor valve will co-act with the said resilient means in opposition to the force tending to close said air bleed valve and hold the air bleed valve slightly open to air bleed the suction impressed upon the suction device to less than the suction obtaining in the intake passageway under such operating conditions.

25. In an internal combustion engine having an intake passageway, mechanism for governing the speed of the engine comprising a governor valve for controlling the flow of fluid through said passageway, a suction actuated device having an operative connection with said governor valve, an orifice located in said passageway on the engine side of said throttle valve, a conduit connecting said orifice with said suction device, an air bleed orifice to atmosphere, a second conduit connecting said air bleed orifice with the suction device and the aforementioned conduit, a centrifugally unbalanced valve responsive to changes in engine speed for controlling said air bleed orifice, said valve itself constituting the centrifugal weight which responds to changes in the engine speed, said air bleed valve tending to close due to centrifugal force as the engine reaches its governed speed and in opposition to the suction from said intake passageway, resilient means opposing the closing of said air bleed valve, the force urging said valve closed when said engine reaches its governed speed being coordinated with the force of the resilient means and the suction from the intake passageway tending to open said air bleed valve whereby when the suction device responds to the intake passageway suction to close said governor valve the suction obtaining in the intake passageway on the engine side of the governor valve will co-act with the said resilient means in opposition to the force tending to close said air bleed valve and hold the air bleed valve slightly open to air bleed the suction impressed upon the suction device to less than the suction obtaining in the intake passageway under such operating conditions.

26. The combination as set forth in claim 25 including a third conduit connecting the suction device with an orifice in the intake passageway on the atmosphere side of said governor valve whereby the orifice between the governor valve and atmosphere plays the role of an air bleed to the other orifice in said intake passageway when the said governor valve moves toward closed position and said orifice between the governor valve and atmosphere ceases to be an air bleed and becomes a suction orifice when the governor valve moves toward open position.

27. In an internal combustion engine having an intake passageway, a device for governing the speed of the engine comprising a governor valve for controlling the flow of motive fluid through said passageway, a device actuated by suction from a point in said passageway between the governor valve and the engine and having an operative connection with said governor valve, a valve housing rotated in accordance with engine speed,

5 a fluid bleed inlet port in said housing, a piston valve reciprocable in said housing along a path transverse to the axis of rotation of said housing, the said piston valve itself being centrifugally unbalanced and responding to changes in engine speed for controlling said fluid bleed orifice, said piston valve tending to close in response to centrifugal force and in opposition to the suction from said intake passageway as the engine reaches its governed speed whereby the governor valve is closed by said suction actuated device in response to the suction impressed upon said suction actuated device from said intake passageway.

28. In an internal combustion engine having an intake passageway, a governor valve for controlling the flow of fluid through said passageway, a suction operated device connected to said valve, a conduit connecting the suction device into the intake passageway on the engine side of said valve, a second conduit connected into said suction device, an ignition distributor shaft rotatable in accordance with the speed of the engine and having a passageway therein communicating with said second conduit, a valve housing fixed on said shaft, the interior of said housing communicating with the passageway in said shaft, an air bleed port in said valve housing, and a centrifugally unbalanced valve mounted within said housing for closing said air bleed port when the shaft reaches a predetermined speed whereby the suction device responds to move said governor valve toward closed position.

29. In an internal combustion engine having an intake passageway, a governor valve for controlling the flow of fluid through said passageway, a suction operated device connected to said valve, a conduit connecting the suction device into the intake passageway on the engine side of said valve, a second conduit connected into said suction device, an ignition distributor shaft rotatable in accordance with the speed of the engine and having a passageway therein communicating with said second conduit, a valve housing fixed on said shaft, the interior of said housing communicating with the passageway in said shaft, an air bleed port in said valve housing, a centrifugally unbalanced valve mounted within said housing for closing said air bleed port when the shaft reaches a predetermined speed whereby the suction device responds to move said governor valve toward closed position, and an ignition distributor housing for enclosing said rotary valve housing.

30. A governor for an internal combustion engine having an intake passageway comprising a throttle valve for controlling the flow of motive fluid through said passageway, a suction actuated device connected to said throttle valve for imparting movement thereto, a conduit connecting said suction actuated device with the intake passageway on the engine side of said governor valve, an air bleed for said suction device, a valve centrifugally controlled in accordance with engine speed for controlling said air bleed, said valve closing at a predetermined engine speed whereby said suction device moves said governor valve toward closed position, the closing of said air bleed valve being opposed by the vacuum from the intake passageway on the engine side of the throttle valve.

31. In an internal combustion engine having an intake passageway, a governor valve for controlling the flow of fluid through said passageway, a suction operated device connected to said governor valve, and a conduit connecting the

suction device into the intake passageway on the engine side of the said governor valve, the improvement comprising a valve housing rotated in accordance with the speed of the engine and having a port to atmosphere external of said passageway, a second conduit connecting the suction device with said valve housing, said first and second conduits being in communication with each other, and a centrifugally unbalanced valve mounted in said housing for radial movement toward and away from the axis of rotation of said housing and tending to close said port to atmosphere whenever the engine attains a predetermined speed whereby the suction device responds to move said governor valve toward closed position, and resilient means tending to hold said valve open in opposition to the centrifugal force tending to close the valve, the said valve being arranged in said housing so that it tends to close said port in opposition to atmospheric pressure, said governor valve being unbalanced so that the suction in the intake passageway on the engine side of the governor valve tends to open said governor valve.

32. A governor for an internal combustion engine having an intake passageway comprising a governor throttle valve for controlling the flow of motive fluid through said passageway, a suction actuated device connected to said governor

throttle valve for imparting movement thereto, a conduit connecting said suction actuated device with the intake passageway on the engine side of said governor valve, an air bleed for said suction device, a valve centrifugally controlled in accordance with engine speed for controlling said air bleed, said valve closing at a predetermined engine speed whereby said suction device moves said governor throttle valve toward closed position, said governor throttle valve being unbalanced so that the suction in the intake passageway on the engine side of the governor throttle valve tends to open said governor throttle valve in opposition to the suction device which moves said governor throttle valve toward closed position in response to intake passageway suction on the engine side of said governor throttle valve when the centrifugal valve closes said air bleed, the said unbalancing of said governor throttle valve keeping the governor throttle valve from plastering shut when the centrifugal valve closes the air bleed.

33. The combination claimed in claim 32 wherein the closing of said centrifugal air bleed valve is opposed by the vacuum from the intake passageway on the engine side of said governor throttle valve.

MARION MALLORY.
